N. Ames.
Hand Stamp.

No 16167

Patented Dec. 2, 1850.

Fig. 1.

Fig. 2.

UNITED STATES PATENT OFFICE.

NATHAN AMES, OF SAUGUS, MASSACHUSETTS, ASSIGNOR TO BOSTON HAND STAMP COMPANY, OF BOSTON, MASSACHUSETTS,

HAND-STAMP.

Specification of Letters Patent No. 16,167, dated December 2, 1856.

To all whom it may concern:

Be it known that I, NATHAN AMES, of Saugus, in the county of Essex and Commonwealth of Massachusetts, have invented 5 a new and useful Automatic Hand-Stamp; and I do hereby declare that the following is a full, clear, and exact description of the construction and operation of the same, reference being had to the annexed drawings, 10 forming a part of this specification.

Figure 1 is a perspective view of the machine, and is intended to be about as large as a stamp of the medium size.

A is a wood, or metallic, handle, with a 15 hole in it as indicated by the dotted lines, for the wire, D D, to play in.

B is the type block, of hard wood or metal, the bottom of which is either engraved or covered with an electrotype, or 20 whatever the printing surface may be. In the upper side is a hole large enough to allow the shank, or lower end of the handle, A, to rock with freedom in any direction. The form of this shank, as also the dimensions of the hole in the block, may be seen 25 by inspecting Fig. 2. Thus hung, like the platen of common printing presses, and other presses, it is obvious that, at whatever angle one would naturally strike, the printing surface will conform to the flat bed, or table, 30 on which the article to be printed is placed. Or, B may be a fixed movable part of A.

C is a wire the upper end of which is fast 35 in the handle, A, while the lower end enters a hole in the block, B,—the hole (see Fig. 2) being small in the center and larger at both ends so as to admit of B's rocking freely in any direction. The object of this wire, C, is to keep the block, B, up to its bearing on 40 the shank, A, and also prevent it, (B), from turning.

D D, is a wire about one fourth of an inch in diameter, bent as seen in Fig. 1, one 45 end of it entering the handle, A, as represented by the dotted lines. The object of the wire's entering the handle, is to prevent the former and those parts attached to it, from turning.

E and F are iron bolts, or arms, fast in 50 the handle, A. Through the outer ends of these are holes for the wire, D D, to play in.

G is a piece of cast, or wrought, iron, with a hole in it of the diameter of the wire,

D D, over which it is slipped and then fastened to it, in the proper place, by means of 55 a pin or screw.

H is a coil-spring, the upper end of which pressing against the arm, F, and lower end against the piece, G, G being fast to D, will always have a tendency to push down the 60 wire, D D, into the position seen in the figure.

I is a strong wire, passing through the piece G, and bent as seen in the figure, for giving motion to the inking roller, K. This 65 wire is prevented from rising too high by means of a screw, or pin, J, against which it strikes, said screw or pin, J, being fast in the handle, A. It is also so long as to carry the roller, K, a little beyond the bottom of 70 the type block, B, seen in the figure, so that K may revolve freely on its axis, and thus pass over the type each time in a new position.

K, the inking roller, has a hole through 75 its center, small in the middle and larger toward each end, so as to rock freely on the wire, I, on which it revolves, being prevented from flying off laterally by means of a nut or pin. This roller may be covered with 80 woolen cloth, deer, or sheep, skin (flesh-side out) or other material capable of holding the desirable quantity of ink.

L is a coil-spring which stretches between the lower part of D D, and the short end of 85 the wire, I,—its object being to give the inking roller, K, the requisite pressure on the bottom of the type-block, B.

Operation: The inking roller, K, being sufficiently charged with ink, the operator takes the handle, A, of the machine, in his hand, and strikes down upon the paper, or article to be printed, exactly as he would if the stamp consisted only of the handle, A, and type block, B. It is obvious, then, that the lower end of the wire, D D, will first strike the article to be printed; the spring, H, will be compressed, the arms, E and F sliding upon the wire, D D; and the roller, K, (being acted upon by two forces; the perpendicular, represented by the block, B; and the diagonal, represented by the wire, I), will first roll over the printing surface, or bottom of the block, B, and then over the back side of the same. Instead of striking 100 the end of the wire, D D, upon the article to

be printed, it will be quite as well to let the former rest upon the latter before commencing to press the handle down. On lifting the stamp, it is also obvious that the com-
5 pressed spring, H, will recoil and carry with it the wire, D D, and the roller, K, back into the position represented in the figure. The farther the piece, G, is from the arm, E, the farther will the roller K (being kept up by
10 the spring L) be carried back from the position in which it is represented in Fig. 1; and vice versa. Thus by one downward motion of the hand, the types are inked (being twice passed over by the roller) and the
15 impression produced; thereby saving all the time that must otherwise be consumed in reeling off the stamp from the platen, or thing to be stamped, to a position over the ink fountain, striking it down for ink, and
20 bringing it back preparatory to making a single impression.

I do not claim, in this machine, the principle by which the inking roller, K, is made

to pass over the bottom and back of the type block, B, but

25

What I claim as new in this machine, and desire to secure by Letters Patent, is—

In combination with the other parts of any stamp to be held in the hand, the leg, or wire, D D, so constructed as to strike the 30 article to be printed, in advance of the type-block, B, and thereby cause the inking roller, as described, to pass over the printing surface while the latter is descending. I do not confine myself to any particular manner, as 35 there may be many, in which the leg, D D, may be made to communicate motion to the inking roller; but I claim this leg, D D, both independently of the inking apparatus, and also combined with it and the other 40 parts of the stamp, in any manner substantially the same as that described.

NATHAN AMES.
